PRINTED FABRIC

Albert W. Baylis, Scarsdale, N. Y.

Application April 25, 1933, Serial No. 667,772

17 Claims. (Cl. 28—32)

This invention relates to printed fabrics, and to a method of production thereof.

It is an object of the invention to produce, by a single continuous operation, using a printing roll substantially only of the width of the fabric to be produced from the warps, a plurality of separate warps. By this invention, warp threads, printed as a single warp, after completion of the printing process, are made effective to produce 10 a plurality of fabrics, each of which is of the width of fabrics for which the printed roll is intended, and each of which is substantially the full length of the warp run through the printing machine. Each fabric, by this process, may even have a substantially identical design left as a result of the 15 imprint on the warp threads as originally arranged.

In the customary method of warp printing, a roll of substantially the width of the fabric to be 20 woven is engraved with the design in its exact proportions as it will finally appear on the fabric. The warp threads, fed to the printing machine, are held in substantially the same lateral spaced relationship relative to each other as that which 25 they will assume in the fabric as finally woven. This spacing, to the eye, may appear slight, and even non-existent; yet there are distinct interstices to provide for the spacing which results, in weaving, with the introduction of the filler threads. On this spacing of the threads, the 30 efficiency of the print is, to a large extent, dependent. Penetration through the threads of the dye, applied during that process, has, in the past, been accomplished by getting the dye down 35 around the sides of the thread in such a relative arrangement. The greater the penetration, the firmer is the combination of dye and fibre, and, finally, the more effective is the printed fabric.

Printing, either of woven fabrics or of the 40 warp threads, before weaving, has very little in common with ordinary printing processes applied to such materials as paper. The threads, given the required spacing, receive the dye from a roller in a manner such that not only a face, but 45 the entire periphery and the internal portions, of the thread receive the dye when an imprint is made. In this invention, it is an object to utilize the customary printing roller of the length used in printing a fabric of ordinary width; but 50 with such a roller, the threads to be printed are arranged so that this roller, intended normally for printing, at a single operation, only a single warp for a single fabric of substantially that same width, will produce threads so printed, not for a single warp for a single fabric, but, in accordance 55

with the particular rearrangement of the threads involved in this invention, for two or more distinct warps, each for a distinct fabric, and each of which may display substantially the same design. 5

In the commerce of printing fabrics, the cost of the operation is proportionately, and many times, even disproportionately, greater for any increase imparted to the width of the fabric so produced. As well another element of such cost 10 is the length of the run of warp threads which must be passed through the printing machine. Not an element of that cost, at least to any material degree, is the number of threads included within a warp. By this invention, in the same 15 printing run, which normally is applied only to produce a set of printed warp threads for a single warp of a predetermined width, and those threads, disposed at that width, disclosing a definite design, more than one set of warps, each, 20 if desired, with substantially the same design, may be produced. Consequently, a marked reduction in the printing cost is accomplished. 25

To facilitate this printing operation, in carrying out certain of the features of this invention, the printing roll may have its printing surface engraved to a sharper degree than is normally found necessary during the customary printing operations. By this device, the threads, at 30 the time of imprint, become more deeply imbedded in, or otherwise come into more effective cooperation with, the dye retained by the cut-out surface. The result is a deposit of dye on the thread and its penetration into the 35 fibres to such degree that, even though the spacing of threads may be decreased below that ordinarily considered necessary, the imprint is as good as, if not an improvement over, the result of the normal printing processes. 40

For printing warp threads according to this process, the threads defining the warp are disposed in a relationship to each other more compact than in printing ordinary warps. The relationship of this new arrangement, that is, the 45 relative compactness, is determined by the number of independent warps to be derived from this single printing. Therefore, if it is desired to secure two warps from the single, simultaneous printing, two warp threads are compacted into 50 the same spacing normally taken up by a single warp thread; if three warps, then three warp threads are so compacted. Therefore, as many times the normal number of warp threads are 55 disposed in a warp for the single printing run

as the number of individual warps to be produced from that single run.

At any time after the compacted warp has been passed through the machine, as, for instance, before fixing the dye, the printed warp threads may be divided up into as many groups as the number or warp threads were increased. In one application of the invention, the warp threads are separated in a regular sequence; 10 they may be reeled upon warp beams, or if a continuous operation be desired, immediately on such separation, the threads, in separated relationship, may be fed to different weaving machines to produce a number of different fabrics. 15 For instance, if two warps are to be produced by the single printing, then every second thread is separated from the single printed warp, and then, still retaining its sequential association with other threads separated with it, is wound 20 upon a beam, or is fed for the next successive steps.

In the particular process just detailed, even with this removal of warp threads, the threads remaining carry the imprint to such degree that 25 the delineation of the design, and this is most markedly a fact where the design is of a spread-out character, although the process has equal application where the design is of a fine-line nature, is sharp, and substantially completely the 30 effect of the original design, as if it had been imprinted normally, appears. The change of imprint between contiguous threads is, by the compacting in the warp for printing, made so slight that each such thread imparts to the particular warp into which it is separated substantially identically the same detail of the design. For instance, when the warp threads have been 35 separated into two or more warps, and the threads have been spread out to the normal width of 40 the fabric, ready for weaving, the final warps thus produced display substantially the same design as that on the original warp. In this particular operation, it is not even necessary, when engraving the design on the print roller, to distort that design. The crowding of the threads 45 in the warp to be printed, together with deeper engraving of the roller, cooperate sufficiently for the purpose of leaving a definite imprint on those threads within a definite area of the same 50 design.

By distorting the design on the printing roller, as well as compacting the threads, in the manner stated, the production of a plurality of printed warps may be attained. In this 55 case, entire sections of warp threads are separated as units from the warp after printing. Each separate unit, in itself, is a warp which, when the threads are brought into the normal position, may be used to produce a warp-printed 60 fabric in the normal manner.

Other objects of this invention will herein-after be set forth, or will be apparent from the description and the drawing, in which are illustrated particular embodiments illustrating the 65 principles of the invention.

The invention, however, is not intended to be restricted to any particular construction or arrangement of parts, or to any particular application of such construction, or to any specific 70 method of operation, or to any of various details thereof herein shown and described, as the same may be modified in various particulars, or be applied in many varied relations, without departing from the spirit and scope of the claimed 75 invention, the illustrations of processes herein

appearing being merely to show some practical applications of the invention.

On the drawing, in which the same reference characters refer to the same parts throughout, and in which are disclosed the illustrations of 5 processes:

Fig. 1 is a view in elevation to illustrate diagrammatically apparatus for carrying out a printing process embodying the invention;

Fig. 2 is a plan view of the diagrammatically 10 illustrated apparatus of Fig. 1;

Fig. 3 is a view in perspective of apparatus designed to carry out the invention in modified form; and

Fig. 4 is a cross-sectional view, transversely 15 of, and at right angles to the direction of, the longitudinal axis of a printing roll, engraved in accordance with the invention.

In one application of the invention, warp threads 10 are disposed, as customarily, in order to form an original warp 12 for printing. The threads may be wound together on a beam 14, or in any other manner retained in a proper assembly in relation to each other. In this instance, the threads leading away from the beam are shown threaded through a proper reed 16 to guide them into a proper relationship to each other in passing through a printing machine 18 the engraved roller 20 of which is there made effective upon the threads. Beyond the 20 machine, the threads may be assembled in a suitable manner to be passed finally to some such device as another reed 22. Reed 22 may include a plurality of sets 24 and 26 of eyes by means of which the threads, after printing, may 25 be guided to beams 28 and 30. The several steps are shown as those of a continuous operation. Although possible, and also facilitating the illustration of the process, it is to be understood that, in preferred operation, the warp 30 threads, retained together by temporary filler thread or picks, will be printed. Thereafter, with the removal of the temporary filler threads, the separation of the thread onto the beams 28 and 30 will be effected. In the structure here 35 disclosed, the arrangement produces, after the printing of the single original warp 12 and the separation thereof, two final warps 32 and 34.

In the first step of arranging threads 10, there 40 are disposed double the normal number of threads customarily run through under a roller 20 for the width of fabric for which that roller is intended. Reed 16 is disposed so that threads 10, winding 45 off beam 14 and then travelling to the printing machine for proper cooperation with roller 20, will be retained in a proper relationship so that each pair of the threads will be pressed into the same space that one, in the normal arrangement, previously had assumed.

In order to cooperate properly in effectuating 50 the printing operation, roller 20, as shown in Fig. 4, may have engraved areas 36, for receiving the dye, made deeper than normally. Then threads, brought up to and passing in proper association to the roller, will be pressed sharply 55 into the recesses of the engraved area, and by that step, becoming more closely related to the dye in the recesses, will more efficiently become impregnated.

After the imprint has been made, and the 60 threads move beyond roller 20, they may be brought into association with reed 22 in the manner above referred to, here to be selectively directed to beams 28 and 30. It is also possible to guide the threads, during their separation, di- 65

rectly to weaving machines, or otherwise to process them as a direct part of a continuous operation. In the separating operation, one set of alternate threads 38 go to and are wound upon beam 5 28, while the other threads 40 are wound upon beam 30. In this separating operation, the threads may remain substantially parallel to each other; yet, by the removal of intervening threads, the threads wound on the beams or fed to the 10 weaving machines are in a proper arrangement for weaving. Even with this elimination from the warp of so many threads, still, since the result of the crowding, with the added efficiency derived from the deep imprint, is that elements of 15 the design imprinted on and carried by adjacent threads 38 and 40 will vary but slightly from each other, the final assembly of threads 38, while to a slight degree different, will bear a substantially accurate delineation of the design disclosed 20 by the assembly of threads 40, as well as of the design as originally engraved on roller 20 and imprinted on warp 12. Final warps 32 and 34 thereby, by the single printing operation and the subsequent separation, have had imparted to them 25 substantially the same design.

In the construction shown on Fig. 3, threads 42 may be made to assume substantially the same relative disposition preliminary to printing. Roller 44, however, instead of being engraved with but 30 a design for a single fabric and substantially of the same form as would be used if but a single warp were being printed, in this case is engraved with two distinct designs 46 and 48. These designs may be of the same or of different character. 35 They are distorted from the appearance of the final design to be reproduced by being compressed. The threads to be printed by such a roller and which finally will be used to produce two warps, in this case, are also compressed into a space approximately one-half of that which they normally 40 would assume, and to a width substantially that of one of the designs on the roller. After the threads have passed printing roller 44 and have been printed, they may be brought to a reed 50 at 45 which they are divided into two sets 52 and 54. The two sets of threads are diverged, beyond the reed, onto beams 56 and 58. It is also possible to effect the division of the warps as a part of a continuous process, as, for instance, by passing 50 the threads continuously to the weaving machines for proper association of filler threads, or for such other processing as may be desired. Before passing either to the beam or to the weaving machine, the threads, after they have been divided into the 55 distinct sets, are brought into a normal disposition for warp threads in producing fabrics. This will result in each set of threads occupying, in the newly formed warps, substantially twice as much space as during the printing process.

60 Many other changes could be effected in the methods of operation set forth, and in the particular means for effectuating those operations, and in specific details thereof, without substantially departing from the invention intended to be defined in the claims, the specific description herein being merely to illustrate actual methods of effectuating the spirit of the invention.

What is claimed as new and useful is:—

1. In the art of manufacturing woven fabrics having predetermined designs depicted thereon, in which the design, at least in part, is produced by a process of printing, which comprises: arranging a plurality of threads to produce a warp for the weaving of a fabric, printing on the warp 70 so formed a predetermined design, and then sep-

arating the printed warp threads into a plurality of individual warps no one of which includes the original warp threads in the original relationship to each other, but the threads of each such individual warp maintaining the same succession 5 as in the original relationship.

2. In the art of manufacturing woven fabrics having predetermined designs depicted thereon, in which the design, at least in part, is produced by a process of printing, which comprises: arranging a plurality of threads to produce a warp for the weaving of a fabric, printing on the warp so formed a predetermined design, and then separating the printed warp threads from each other and into groups to leave the effect in each group 10 of the predetermined design, but so that no pair of the original warp threads remain in the original relationship to each other.

3. In the art of manufacturing woven fabrics having predetermined designs depicted thereon, in which the design, at least in part, is produced by a process of printing, which comprises: arranging a plurality of threads to produce a warp for the weaving of a fabric, printing on the warp so formed a predetermined design, and then separating the printed warp threads from each other and into groups to leave the effect in each group 15 of the predetermined design, but so that no pair of the original warp threads remain in the original relationship to each other.

4. In the art of manufacturing woven fabrics having predetermined designs depicted thereon, in which the design, at least in part, is produced by a process of printing, which comprises: arranging a plurality of threads to produce a warp for the weaving of a fabric, printing on the warp so formed a predetermined design, and then separating the printed warp threads into a plurality of individual warps each of which includes the original warp threads not in the original relationship to each other but in the same succession 30 as in the original relationship.

5. In the art of manufacturing woven fabrics having predetermined designs depicted thereon, in which the design, at least in part, is produced by a process of printing, which comprises: arranging a plurality of threads to produce a warp for the weaving of a fabric, printing on the warp so formed a predetermined design, and then separating the printed warp threads from each other in a predetermined succession and into groups to define a plurality of distinct warps each 35 having the effect of the predetermined design but so that no pair of the original warp threads remain in the original relationship to each other.

6. In the art of manufacturing woven fabrics having predetermined designs depicted thereon, in which the design, at least in part, is produced by a process of printing, which comprises: arranging a plurality of threads to produce a warp for the weaving of a fabric, printing on the warp so formed a predetermined design, and then separating the printed warp threads from each other in a predetermined succession and into groups to define a plurality of distinct warps each having the effect of the predetermined design.

7. In the art of manufacturing woven fabrics having predetermined designs depicted thereon, in which the design, at least in part, is produced by a process of printing, which comprises: arranging a plurality of threads to produce an original warp for the weaving of a fabric, printing on the warp so formed a predetermined design, and then separating the printed warp threads into a plurality of warps each consisting of alternate original warp threads maintained in the original relationship to each other so that each 65

of the newly defined warps has a design on the face thereof substantially similar to the originally imprinted design.

8. In the art of manufacturing woven fabrics having predetermined designs depicted thereon, in which the design, at least in part, is produced by a process of printing, which comprises: arranging a plurality of threads to produce a warp for the weaving of a fabric, printing on the warp so formed a predetermined design, and then separating the printed warp threads into a plurality of individual warps, each of the individual warps consisting of original warp threads but only of non-consecutive threads having a predetermined sequential order in the original warp, said non-consecutive threads being maintained in the original relationship to each other so that each of the newly defined warps has a design on the face thereof substantially similar to the originally imprinted design.

9. In the art of manufacturing woven fabrics having predetermined designs depicted thereon, in which the design, at least in part, is produced by a process of printing, which comprises: arranging a plurality of threads to produce a warp for the weaving of a fabric, printing on the warp so formed a predetermined design, then separating the printed warp threads into a plurality of individual warps, each of the individual warps consisting of original warp threads but only of non-consecutive threads having a predetermined sequential order in the original warp, said non-consecutive threads being maintained in the original relationship to each other so that each of the newly defined warps has a design on the face thereof substantially similar to the originally imprinted design, and interweaving the newly defined warps to produce a plurality of fabrics each of which has substantially the same surface design.

10. In the art of manufacturing woven fabrics having predetermined designs depicted thereon, in which the design, at least in part, is produced by a process of printing, which comprises: arranging a plurality of threads crowded together in excess of the usual number for printing threads in the production of a printed warp for the weaving of a fabric, subjecting the warp so formed to deep-cut roll printing to dye all the threads with a predetermined design, and then separating the printed warp threads into a plurality of individual warps each having a complete printed design and all the threads in each individual warp being disposed in a relationship different from their relationship in the original warp.

11. In the art of manufacturing woven fabrics having predetermined designs depicted thereon, in which the design, at least in part, is produced by a process of printing, which comprises: arranging a plurality of threads crowded together in excess of the usual number for printing threads in the production of a printed warp for the weaving of a fabric of a predetermined width, printing on the warp so formed a predetermined design, and then separating the printed warp threads, rearranged in a more widely spaced relation to each other than when printed, into a plurality of warps each newly arranged warp being of the same effective width as the original warp and carrying a complete printed design.

12. In the art of manufacturing woven fabrics having predetermined designs depicted thereon, in which the design, at least in part, is produced by a process of printing, which comprises: ar-

ranging a plurality of threads crowded together in excess of the usual spacing for printing threads for the production of a printed warp for the weaving of a fabric of a predetermined width, printing on the warp so formed a predetermined design, then separating the printed warp threads, rearranged in a more widely spaced relation to each other than when printed, into a plurality of warps no one of which includes two or more of the original warp threads in the original relationship to each other but each newly arranged warp being of the same effective width as the original warp, and interweaving the newly defined warps to produce a plurality of fabrics each having substantially the same surface design.

13. In the art of manufacturing woven fabrics having predetermined designs depicted thereon, in which the design, at least in part, is produced by a process of printing, which comprises: arranging a plurality of threads crowded together to position in the space provided for a single thread in ordinary operations threads to a density of a proportional relationship a multiple of the number of threads customarily used for the production of a printed warp for the weaving of a fabric of a predetermined width, printing on the warp so formed a predetermined design, and then separating the printed warp threads into a plurality of individual warps in which the threads are positioned in the normally spaced relationship for weaving, each of said individual warps carrying a complete printed design.

14. In the art of manufacturing woven fabrics having predetermined designs depicted thereon, in which the design, at least in part, is produced by a process of printing, which comprises: arranging a plurality of threads crowded together to position a multiple number of the threads in the space provided for a single thread in ordinary operations for the production of a printed warp for the weaving of a fabric of a predetermined width, printing on the warp so formed a predetermined design, and then separating the printed warp threads into a plurality of individual warps in which the threads are positioned in the normally spaced relationship for weaving, the number of individual warps so produced being the same as the multiple number of the crowded threads, each of said individual warps carrying a complete printed design.

15. In the art of manufacturing woven fabrics having predetermined designs depicted thereon, in which the design, at least in part, is produced by a process of printing, which comprises: arranging a plurality of threads crowded together to position in the space provided for a single thread in ordinary operations threads to a density in a multiple proportional relationship to the number of threads customarily used for the production of a printed warp for the weaving of a fabric of a predetermined width, printing on the warp so formed a predetermined design, and then separating the printed warp threads into a multiple number of individual warps in which the threads are positioned in the normally spaced relationship for weaving, the multiple of the number of individual warps so produced being the same as the multiple of the proportional relationship of the density, each of said individual warps carrying a complete printed design.

16. In the art of manufacturing woven fabrics having predetermined designs depicted thereon, in which the design, at least in part, is produced by a process of printing, which comprises: arranging a plurality of threads crowded together

to position in the space provided for a single thread in ordinary operations threads to a density in a multiple proportional relationship to the number of threads customarily used for the production of a printed warp for the weaving of a fabric of a predetermined width, subjecting the warp so formed to deep-cut roll printing to produce on all the threads a predetermined design, and then diverging the printed warp threads to define a multiple number of individual warps in which the threads are positioned in the normally spaced relationship for weaving, the multiple of the number of individual warps so produced being the same as the multiple of the proportional relationship of the density, each of said individual warps carrying a complete printed design.

17. In the art of manufacturing woven fabrics having predetermined designs depicted thereon, in which the design, at least in part, is produced by a process of printing, which comprises: ar-

5 ranging a plurality of threads crowded together to position in the space provided for a single thread in ordinary operations threads to a density in a multiple proportional relationship to the number of threads customarily used for the production of a printed warp for the weaving of a fabric of a predetermined width, subjecting the warp so formed to deep-cut roll printing to produce on all the threads a predetermined design, and then diverging the printed warp threads to 10 define a multiple number of individual warps in which the threads are positioned in the normally spaced relationship for weaving, the multiple of the number of individual warps so produced being the same as the multiple of the proportional 15 relationship of the density but each newly arranged warp being of the same effective width as the original warp, each of said individual warps carrying a complete printed design.
